UNITED STATES PATENT OFFICE.

JAMES A. CHARNLEY, OF PROVIDENCE, RHODE ISLAND.

ORNAMENTAL WIRE.

SPECIFICATION forming part of Letters Patent No. 253,184, dated February 7, 1882.

Application filed January 19, 1880.

To all whom it may concern:

Be it known that I, JAMES A. CHARNLEY, of Providence, in the State of Rhode Island, have invented a new and useful Ornamental 5 Wire; and I do hereby declare that the following specification, taken in connection with the drawings, making a part of the same, is a full, clear, and exact description thereof.

Figure 1 shows a piece of wire ornamented 10 a portion of its length. Fig. 2 is an enlarged section of the same. Fig. 3 is an end view of same. Fig. 4 is a piece of wire ornamented a portion of its length with another design. Fig. 15 5 is a section of same enlarged. Fig. 6 is an end view of same. Fig. 7 is a side elevation of a pair of die-rolls provided with the design, cut spirally thereon, for ornamenting the wire between them.

The object of my invention is to produce a 20 wire suitable for making or ornamenting jewelry and fancy articles; and it consists in a new article of manufacture, as hereinafter described.

Plain gilt or plated wire has, I am aware, 25 been used for the purposes above mentioned.

In my invention I produce a wire upon the exterior of which is engraved, cut, or stamped, in a cylindrical direction around it, any suitable design, the wire having been previously 30 drawn in the usual way, and subsequently plated, if desired. Wire has never before been ornamented in this manner, owing to the impracticability of engraving it by hand and the want of suitable machinery.

35 In producing my improved wire I first draw it in the usual way, (A, Figs. 1 and 4,) after which it is cut into suitable lengths and straightened. I then subject it to the action of two fine die-

rolls by passing it while perfectly straight longitudinally through them, both of said rolls rotating in the same direction. These rolls rotating in the same direction will be found to hold and turn the wire, and at the same time engrave, cut, or stamp upon its exterior surface, as it passes through them, the same design or ornamentation which has been previously cut upon the rolls, as shown at B, Figs. 1 to 40 6, inclusive. The rolls are adjusted with reference to each other according to the size of the wire to be introduced. The end of the wire 45 is by the aid of pinchers forced in between the two rolls, having the design cut spirally thereon, after which, upon motion being imparted thereto, as described, it will be found that their engraved surfaces will cut or indent 50 a similar design in a cylindrical direction continuously over and upon the entire surface of the wire while being fed in a longitudinal direction, (see Fig. 7,) which I believe has not heretofore 55 been accomplished in the history of this art. 60 As the spirally-engraved rolls and mechanism used in connection therewith constitute an invention for which I intend to apply for Letters 65 Patent, a further description thereof is unnecessary here.

What I claim as my invention, and desire to secure by Letters Patent, is—

As a new article of manufacture, a flexible wire having engraved or depressed upon its exterior surface any suitable design or ornamentation, substantially as and for the purposes specified.

JAMES A. CHARNLEY.
